Application October 20, 1952, Serial No. 315,712

Claims priority, application Sweden October 24, 1951
3 Claims. (Cl. 236—35.2)

It is previously known in automobiles to control automatically the temperature of the cooling fluid of internal combustion engines by means of a radiator shutter mechanism containing vanes the ends of which are pivotally mounted in a frame and which are rockable into their open position by means of a control device the length of which is variable in response to temperature variations in the cooling fluid so as to cause an extension of said control device upon the cooling fluid temperature being increased, and vice versa, said control device being, in order to cause transmission of its movements to said shutter vanes, connected with at least one movable tie bar or the like having means for cooperation with the pivots or trunnions of the shutter vanes mounted in said frame.

The present invention relates to an arrangement of 30 the kind indicated above which is extremely reliable and safe of operation and which is mainly characterized by the fact that said tie bar is in the form of a slide vertically displaceable on a lateral side-surface of said frame and is formed with guide slots, each vane pivot is extended outward and bent over into a reversed direction engaging one of said guide slots, whereby the angular position of said shutter vanes is varied by any displacement of said slide brought about by the action of said control device.

The invention will now be described more in detail in conjunction with an embodiment thereof illustrated in the accompanying drawings and according to which two separately controlled sets of radiator shutters are used.

In the drawings:

Fig. 1 is a frontal view, partly in section, of the control-side of the shutter mechanism showing the shutter vanes in their closed position.

Fig. 2 is a side view showing the mechanism from the control-side, the cover protecting the movement transmitting elements and the control device being removed, the shutter vanes being shown in the same position as in Fig. 1. Fig. 3 is a view similar to Fig. 2 but with one set of shutter vanes in its fully open position and the other vane set in a partly open position; and Fig. 4 is a perspective view of a portion of the control side of the shutter mechanism.

Referring to the drawings, a frame 1 which is substantially rectangular in shape is placed around a radiator. The frame consists of a pair of parallel side members 20 which are connected by top and bottom members 21 and 22. The frame members are made from channel steel having a web portion 20a joining side walls 20b and 20c. The members are assembled with web portions 20a facing inwardly of the frame. Shutter vanes 2 are pivotally mounted at their ends in openings 23 in the web portions 20a of the two vertical side members 20 of the frame. The mounting pivots or trunnions 3 extend through the openings 23 in the web portions 20a and are bent over into a substantially U-shape.

In at least one upper corner of the rectangular frame,

the vertical side member 20 is broadened into a plate-like member 24. The web portion 24a extends horizontally along the lower edge of the plate-like member 24 and then vertically along the inside edge thereof. This plate-like corner member 24 and its web portion 24a define a recess in one corner of the frame into which a control device in the form of a bellows-like arrangement 6 is positioned. A bracket support 7 is mounted on the plate-like corner member 24 to which the bellows-like arrangement 6 is connected. On the opposite end of the bellows-like arrangement 6 is attached a horizontal support 8 having a downwardly extending leg 8a on one end thereof and an upwardly extending leg 8b on the other end thereof.

Reinforcement bars 16 are secured to the web portion inside and adjacent to one of the side walls of a vertical channel member. The mounting pivots 3 extend through openings 25 in these reinforcement bars as well as through the web portion 20a. A similar reinforcement bar 16a is mounted on the web portion 24a of the corner plate 24, and the mounting pivots 3 of the shutters in the upper portion of the frame 1 extend through openings 25a in this reinforcement bar 16a as well as through the web portion 24a of the corner plate 24.

Between the edge of the reinforcement bar 16 which is spaced from the other side wall of the channel member is a lower slide 9. The downwardly extending leg 8a of the horizontal support 8 is connected to the upper end of this slide 9. An upper slide 10 is mounted between the connecting edge of the reinforcement bar 16a and the corner plate member 24, and this slide is attached to the upwardly extending leg 8b of the horizontal support 8. The slides are thus mounted for sliding movement parallel to a line passing through the apertures for the mounting pivots 3 in the web portion 20a of the frame 1. The said slide portions 9 and 10, therefore, will be moved in downward direction as a unit upon extension of the control device 6. The vane pivots 3 are

35 rotatably mounted in holes through web portion 20a and reinforcement 16, and the extremity 4 of the U-shaped end portion of each vane pivot 3 is directed towards the slides 9 and 10 and engages a corresponding one of the openings in the form of guide slots therein, as will be explained in the following description. To the end of the control member connected with said rigid support 7 a fluid conduit 11 is connected through which the control device is in communication with a steam generator (not shown) which is inserted in the fluid conduit between the engine and the radiator. The steam generator is filled with acetone or any suitable other volatile fluid which, on a given temperature being reached by the cooling fluid of the engine, will evaporate and fill the conduit 11 and the control device 6 with vapor which, on reaching a predetermined pressure, will cause the control device 6 to be extended causing displacement of the slides 9 and 10.

40 The slides 9 and 10 are, as previously mentioned, provided with openings in the form of guide slots, one for each vane pivot extension, the slots comprising a portion 12 or 14 extending longitudinally of the slide and a portion 13 or 15 extending transversely thereto. The bent-over end portions 4 of the vane pivots 3 thus project into guide slots and are guided therein when the slides are displaced. This arrangement is such that each one of a lower group of guide slots, formed in the slide 9, consists of a lower portion 14 extending longitudinally of the slide 9, and an upper portion 15 extending transversely thereof, and each one of an upper group of guide slots, formed in the slide 10, consists of a lower portion 13 extending transversely, and an upper portion 12 extending longitudinally of the slide 10. The said trans-

3

versely extending portions 13, 15 of the guide slots depart from the corresponding longitudinal portions 12, 14 in a direction leading away from the corresponding vane pivots 3. The transversely extending portions of the guide slots may extend perpendicularly to the longitudinal direction of the slides, as shown at 13, but it is preferred, in order to facilitate the pivot end portions 4 preferred, in order to facilitate the pivot end portions 4 to sliding into the same, that they extend at an angle to said longitudinal direction, as shown at 15.

In the embodiment illustrated, the longitudinally extending portions 12, 14 of the guide slots are defined partly by a lateral edge of recesses made in one longitudinal edge of the slides 9 and 10, and partly by the straight longitudinal edge of the reinforcement 16 which serves as a guide member along which the slides are longitudinally displaceable in the manner illustrated.

Further, in the embodiment illustrated, the shutter vanes 2 and slots for the bent over ends of the pivots 3 are thus divided into two sets and so arranged that the upper shutter vane set, comprising in this instance four vanes which are made shorter than the lower vanes in order to accommodate the recess for the control device 6, will be opened in advance of the lower set, the latter comprising in this instance seven vanes. It is for this purpose that the slots are made different in the two sets. In the upper set the transverse portion 13 of the guide slot is adapted in a first portion of the opening movement of the slide 10 to move the pivot end portion 4 causing the latter to rock due to the fact that the pivot end portion 4 projects into the transverse portion 13 of the slot, whereby the shutter vane mounted on this pivot will be angularly adjusted into its open position. Thereafter the longitudinal portion 12 of the slot will allow continued displacement of the slide 10 which movement is unobstructed by the pivot end portion 4 projecting into the guide slot. In the lower set the longitudinally extending portion 14 is adapted to permit a limited opening movement of the slide 9 without actuation of the lower shutter vane set, and the transversely extending portion 15 is adapted upon termination of the opening movement of the slide 10 to move the pivot end portion 4 projecting into the same and thereby cause opening of the lower shutter vane set.

It will be understood that the embodiment illustrated and described is to be considered merely by way of example, and that the invention may be varied within the scope of the appended claims.

What we claim and desire to secure by Letters Patent is:

1. In a mechanism for automatically controlling the cooling liquid temperature of internal combustion engines for vehicles, said mechanism having disposed in front of the radiator of said vehicle a substantially rectangular frame with substantially vertical side channel members connected by top and bottom members, said vertical members having their web portions facing inwardly of the frame with a plurality of openings therein, shutter vanes mounted in said frame having pivots on the

ends thereof extending through the openings in said web portions, and regulator means on said frame having a portion thereof movable in dependence on the temperature of the cooling liquid, that improvement comprising at least one reinforcement bar having one straight edge mounted on said web portion adjacent to one of the channel side walls and having a plurality of openings therein through which the pivots on said vanes extend, and at least one slide slidably mounted against said web portion between said reinforcement bar and a side wall of the vertical frame member and having a plurality of guide slots therein, the ends of said pivots being bent over and engaged in said openings, and said slide connected to said regulator means and movable thereby in response to a temperature change of said cooling liquid.

2. The improvement as claimed in claim 1 in which at least one of the vertical side members of the frame is broadened near the top to form a corner plate on which said regulator means is mounted, said corner plate having a web portion on the inner edge thereof perpendicular to said plate, and in which there are two of said reinforcement bars, one on the web portion of the vertical member of said frame and one on the web portion of the corner plate, and two of said slides, one between the reinforcement bar on the web of said corner plate and said corner plate, and said openings in said slides are in the form of slots, each slot in the slide on the web of the corner plate comprising a lower, transversely extending portion and an upper, longitudinally extending portion, and each slot in the slide on the web of the vertical member of the frame comprising a lower, longitudinally extending portion and an upper, transversely extending portion, the transversely extending portions of said slots departing from the longitudinally extending portions thereof in a direction away from said pivots.

3. The improvement as claimed in claim 2, said slides having recesses in the longitudinal edges thereof adjacent the edge of said reinforcement bars, the said longitudinally extending portions of said slots being defined partly by a lateral edge of said recesses and partly by the edge of said reinforcement bars beneath which said slides are slidable.
